UNITED STATES PATENT OFFICE

JOSEPH WRIGHT, OF PHILADELPHIA, PENNSYLVANIA.

UMBRELLA FOR CHILDREN'S CARRIAGES.

SPECIFICATION forming part of Letters Patent No. 336,879, dated February 23, 1886.

Application filed August 10, 1885. Serial No. 174,069. (No model.)

To all whom it may concern:

Be it known that I, JOSEPH WRIGHT, a citizen of the United States, and a resident of Philadelphia, Pennsylvania, have invented 5 certain Improvements in Umbrellas for Children's Carriages, of which the following is a specification.

My invention relates to that class of umbrellas for children's carriages in which the 10 umbrella is supported above the curved standard secured to and projecting over the carriage-body, the objects of my invention being to permit the ready application of the umbrella to and the ready detaching of the same 15 from the standard, and the avoidance of a multiplicity of parts in the attachment.

In the accompanying drawings, Figure 1 represents my improved carriage-umbrella applied to the standard, and showing the relation 20 of the umbrella to the body of the carriage. Fig. 2 is an enlarged section, partly in elevation, of sufficient of the standard and of the frame of the umbrella to show the means of attachment employed; Fig. 3, a sectional view, 25 partly in elevation, showing the frame of the umbrella detached from the standard and closed; and Figs. 4 and 5, views illustrating modifications of the invention.

A represents the curved standard, which is 30 secured to the back of the carriage and projects over the body of the same, as usual.

B is the stick of the umbrella, to which is secured the usual notch, a, and to the latter are hung the upper ends of the ribs b, D being 35 the runner, to which are hung the inner ends of the stretchers d, the outer ends of the latter being connected to the ribs b, as usual.

As shown in Figs. 1 and 2, the standard A has at the front end a vertical socket, F, 40 adapted for the reception of the lower end of the stick B of the umbrella, said stick having a spring-retainer, f, similar to that of an ordinary umbrella or parasol.

Before applying the umbrella to the stand- 45 ard it is spread by passing the stick down through the runner until the retainer is below the lower edge of the latter, the stick being then grasped by the knob g at the upper end, and the lower end of the stick thrust into the 50 socket F of the standard until the retainer

enters a slot, h, in said socket, as shown in Fig. 2, thereby retaining the umbrella firmly in place on the standard.

When it is desired to detach the umbrella, the spring-retainer f is depressed in order to 55 permit the removal of the stick from the socket F, and is then again depressed, so as to release the retainer D and permit the descent of the same and the closing of the umbrella, as shown in Fig. 3. 60

The use of the socket F on the standard is not necessary to the proper carrying out of my invention. For instance, in the modification shown in Fig. 4 the standard is simply bent upward at the end, and is provided with 65 a spring-retainer, f, adapted to a slot, i, in the retainer D. In this case the umbrella is spread by lifting the runner until the short stick B enters the upper end of the same, the stretchers being then straight, as shown, so 70 that there is no tendency of the umbrella to collapse. The runner is then thrust onto the upturned end of the standard until the retainer f enters the slot i, and prevents the removal of the umbrella from said standard. The stick 75 B may in this case serve by contact with the upturned end of the standard as a stop to limit the downward movement of the runner onto the standard.

Fig. 5 shows a modification of a substantially 80 similar character to that shown in Fig. 4, the only difference being that in this case, instead of the wooden stick B, the notch of the umbrella forms part of a short metal tube, which takes the place of the stick and fits over the 85 upturned end of the standard, the latter being reduced in diameter for the reception of the tube. A knob, g, is secured to the upper end of the tube, to facilitate the handling of the latter. 90

Instead of turning up the end of the standard to form a support for the umbrella, a vertical pin may be secured to the end of the standard; but the plan of simply turning up the end is the simplest and is preferred. 95

I claim as my invention—

1. The combination of the umbrella with a standard having an upwardly-projecting end constructed for the reception of the stick or runner of the umbrella, and a spring-retainer 100

whereby the removal of the latter is prevented, all substantially as set forth.

2. The combination of the umbrella, the stick of which has a spring retainer, with the 5 standard having a socket constructed for the reception of the lower end of said stick, and slotted for the reception of the spring retainer carried thereby, all substantially as specified.

In testimony whereof I have signed my name to this specification in the presence of two to subscribing witnesses.

JOSEPH WRIGHT.
